RALPH B. CARTER, OF BLOOMINGTON, INDIANA, ASSIGNOR, BY DIRECT AND MESNE ASSIGNMENTS, OF ONE-HALF TO THEODORE J. LOUDEN, OF BLOOMINGTON, INDIANA.

SIGNAL APPARATUS.

1,171,770.

Specification of Letters Patent. Patented Feb. 15, 1916.

Application filed June 7, 1913. Serial No. 772,266.

To all whom it may concern:

Be it known that I, RALPH B. CARTER, a citizen of the United States, and a resident of Bloomington, county of Monroe, and 5 State of Indiana, have invented a certain new and useful Signal Apparatus; and I do hereby declare that the following is a full, clear, and exact description thereof, reference being had to the accompanying 10 drawings, in which like letters refer to like parts.

The chief object of this invention is to simplify and cheapen vastly the installation and operation of signal apparatus, such as 15 fire alarms and burglar alarms, as compared with the present burglar alarm systems, fire alarm systems and the like.

The chief feature of the invention consists in utilizing a telephone system with 20 which a subscriber is connected for signal purposes other than telephones, the various signals being different so that the operator at the central station can readily distinguish them. Thus a burglar alarm and a 25 fire alarm in the building may be connected with the telephone circuit running into such building so that they may be operated in connection with the central telephone station and battery, and without installing 30 additional battery. In this connection not only the telephone line, but the central station and battery are employed. Thus when a fire occurs, the fire alarm apparatus connected with the telephone circuit will give 35 the signal to the operator at the central station of the telephone. The same thing is true of the burglar alarm apparatus. The burglar and fire alarm apparatus are located in the telephone circuit and leave the 40 circuit normally open so that they will not interfere with the use of the telephone at any time at least when they are not operating. Such an arrangement of fire alarm or burglar alarm for a building can be very 45 cheaply installed because it renders needless the establishment of additional connections between a central station and the alarm apparatus or adding other battery. For a very small sum of money a fire alarm can

be placed in a room and connected with the 50 telephone line. The same thing is true of the burglar alarm. Therefore, this invention will render it possible for people living in the country and in small towns to have a firm alarm apparatus at nominal expense 55 within the reach of all. It also would provide burglar alarm equipments in cities at much less than the cost of the systems now in use. When once installed, the apparatus needs no attention from the sub- 60 scriber.

The full nature of the invention will be understood from the accompanying drawings and the following description and 65 claims:

In the drawings, Figure 1 is a diagram of a telephone circuit and an alarm apparatus. Fig. 2 is an elevation of a thermostat for a fire alarm apparatus. Fig. 3 is an elevation of the clock anywhere in the burglar alarm apparatus, part of the face being broken away. Fig. 4 is a section on the line 4—4 of Fig. 3. Fig. 5 is a perspective view of the insulating strips in the wheel of the clock. 75

In detail there is shown herein a central telephone station 10 from which the usual telephone circuit extends consisting of the wires 11 and 12, equipped with a battery 50. On this line there is a telephone 13 which bridges or closes the circuit when the telephone is in use, but when the telephone is not in use, the circuit is open. Beyond the telephone there is a burglar alarm apparatus adapted also to bridge or close the 80 circuit when the switch 15 is closed by a burglar or otherwise, but it normally leaves the circuit open. Beyond the burglar alarm there is a fire alarm apparatus 16 adapted to bridge and close the circuit when 85 fire occurs, but which leaves the circuit normally open. 90

The telephone has a light signal 17 at central, the burglar alarm has a slowly repeating signal 18 and the fire alarm has a 95 rapid signal 19, which signals are clearly different in character and distinguishable by the operator at the central station. Thus

the fire signal 19 vibrates much more rapidly than the signal 18, and these signals may be otherwise varied so long as they may be clearly distinguishable by ear or 5 eyes of the operator at the central station, so that she will know whether there is a telephone call or a fire or a burglar alarm.

Going further into the details of construction of the apparatus in order to explain the nature thereof and enable others skilled in the art to construct the same, the fire alarm apparatus 16 contains a thermostatic device in the form of a thermometer 20 having therein a float 21 carrying a 10 downwardly turned wire or arm 22 with a projection 23 thereon extending outward in position to engage either the terminal 24 or 25. A wire 26 runs from terminal 24 to the rapid signal 19 which is connected 15 with the wire 11 of the telephone circuit. The terminal 25 is connected by wire 125 with a slower signal 119 which is also connected with wire 11. The wire 12 of the circuit is connected with the bulb of the 20 thermometer. When the heat becomes excessive, the fluid in the thermometer expands and causes the point 23 on the wire 22 to engage the terminal 24 and close the circuit and give the fire signal at the central 25 station. Low temperature will cause the projection 23 to engage terminal 25 and the slower signal 119 and give warning at the central station.

In the burglar alarm apparatus, the 30 switch 15 may be made in any form employed in burglar alarm systems so as to be closed by the burglar and is connected with the telephone circuit through lines 114, 14 and 34 and 130, 230 and 35. The signal 35 apparatus 18 includes a magnet connected with the circuit and has a pendulum or swinging armature 30 normally out of contact with the core of the magnet, but adapted to be attracted when the magnet is energized, but the pendulum arrangement of the part 30 and its size and weight prevent its rapid movement so that it gives a very slow repeating signal distinguishable from the other signals employed.

50 The burglar alarm apparatus is preferably cut out from the telephone circuit during the day time. This may be done by a hand operated switch 31 for closing the terminals 32 and 33, but it is preferable that 55 such be automatic because if the burglar alarm apparatus be connected, say, with the front door of the office of establishment, the proprietors or employees could not enter without operating the burglar alarm. In 60 order to prevent this result, a clock mechanism is employed which cuts out the burglar alarm apparatus in the morning before the time for beginning work. To that end a clock 40 is shown having a wheel 41 which 65 is driven by the clock through a shaft 42.

The wheel 41 is connected with the telephone circuit by the wire 14 and brush 36. A segmental shaped block of insulating material 44 is secured in the face of the wheel 41 and another segmental block 45 fits in 70 an annular groove 46 of said wheel and has secured to it a finger 47 which projects through the face of the clock so that a person can adjust the position of the block 45 on the wheel 44 in relation to the block 44. 75 A brush 48 engages the blocks 44 and 45 on the face of the wheel 41 as it revolves and closes the circuit when it engages the wheel 41 through the wire 114. The brush 48 fits over the upper end of the shaft 42 80 and is insulated therefrom by an insulation 49. The wheel 41 is a twenty-four hour wheel and during the major portion of its revolution the brush 48 is in engagement with the metallic portion of the wheel and, 85 therefore, cuts the burglar alarm apparatus into the telephone circuit. This is the time between closing and beginning business. During working hours the burglar alarm is not in contact with the wheel 41, but is in 90 contact with the blocks 44 and 45. The length of time during which the burglar alarm apparatus is cut out of the circuit is predetermined by the adjustment of the insulating block 45 which can be done 95 through the movement of the finger 47.

The low temperature signal referred to herein informs the operator at the central station of the condition of the temperature in the places where the thermometer is located and is useful in connection with buildings and plants where it is desired to safeguard against a low temperature. 100

The invention is:

1. Apparatus of the kind described including a telephone circuit and a central telephone exchange station, battery and subscriber's telephone connected therewith, fire alarm apparatus connected with said circuit, burglar alarm apparatus connected with said circuit, said telephone, fire alarm apparatus and burglar alarm apparatus including means to open the circuit when not in use and to close it when operated, and each also including a signaling means, a signal operable by the telephone and by each alarm signaling means, the signaling means in connection with the burglar alarm apparatus repeating more slowly than the fire alarm signaling means, said circuit controlling and signaling means of each alarm apparatus being serially included in independent bridges of the telephone circuit. 115

2. Apparatus of the kind described including a telephone circuit and a central station, battery and telephone connected therewith which opens the circuit when not in use, a thermometer connected with one side of the circuit, a plurality of distinguishable signals connected with the other side 120 130

of the circuit and having independent terminals, and means controlled by the thermometer for engaging one of said terminals when the temperature is high and for
5 engaging the other terminal when the temperature is low.

In witness whereof, I have hereunto af-

fixed my signature in the presence of the witnesses herein named.

RALPH B. CARTER.
